1 REACTOR

TECHNICAL FIELD

This invention relates to a reactor.

BACKGROUND ART

Recent years have seen an increasing demand for down-sizing power converters and increasing output. It is generally known that increasing a switching frequency of a semiconductor element included in a power converter can downsize a reactor included in the power converter. However, increase in the switching frequency increases the quantity of heat generated in cores of the reactor. Moreover, downsizing the reactor reduces a heat dissipation area. Thus, the heat dissipation from the cores decreases.

Furthermore, cores of conventional reactors are covered with a resin case with a low thermal conductivity. A coil made of copper or aluminum is wound around the resin case. Thus, high thermal resistance from the cores of the reactor to the atmosphere outside the coil, and low heat dissipation become problems.

In the reactor, gaps (hereinafter referred to as "core gaps") are formed in magnetic paths of the cores for obtaining desired electrical characteristics. Linkage of the magnetic flux leaked from the core gaps with the wound coil causes an eddy-current loss in the coil. It is generally known that increase in the length of the core gap increases the eddy-current loss. Approximately only three core gaps at most are formed in a reactor for increasing the productivity of the reactor, which causes problems of increase in the length per core gap and increase in the eddy-current loss in the coil.

Patent Document 1 describes increasing the heat dissipation in the reactor by filling a heat-dissipating case for housing the reactor with an elastic resin or insulating oil.

SUMMARY

Problem to be Solved by the Invention

In the reactor of Patent Document 1, however, the cores are covered with an elastic resin with a low thermal conductivity. Thus, thermal resistance from the core to the heat-dissipating case is high, and the heat dissipation from the cores is low. Since the divided cores are bonded via, for example, an adhesive, low precision in the length of the core gap and increase in the eddy-current loss in the coil due to the magnetic flux leaked from the core gaps become problems.

The present invention has been conceived to solve the problems, and has an object of providing a reactor including cores with higher heat dissipation and a coil with less eddy-current loss.

Means to Solve the Problem

A reactor according to the present invention includes: a plurality of divided cores having a shape obtained by dividing an annular core in a circumferential direction, the

2

divided cores being made of a soft magnetic material; a core gap part disposed between the divided cores in the annular core formed by combining the plurality of divided cores, the core gap part being made of a non-magnetic material; annular heat-dissipating cases that house the divided cores and the core gap part; and a coil wound around the heat-dissipating cases. The heat-dissipating cases are made of a material whose thermal conductivity is as high as 100 W/(m·K) or more.

Advantages of the Invention

The reactor according to the present invention can achieve the high heat dissipation from the divided cores by dissipating the heat generated in the divided cores from the heat-dissipating cases. Further, since the core gaps are distributed into a plurality of portions according to the number of divided cores, the eddy-current loss of the coil caused by the linkage of the magnetic flux leaked from the core gaps with the coil can be reduced. The object, features, aspects and advantages of the present invention will become more apparent from the following detailed description and the accompanying drawings.

BRIEF DESCRIPTION OF DRAWINGS

FIG. 1 illustrates a perspective view of a reactor according to Embodiment 1.

FIG. 2 is a sectional view of the reactor according to Embodiment 1.

DESCRIPTION OF EMBODIMENTS

Embodiments of the present invention will be hereinafter described. In different Embodiments, the same reference numerals will be assigned to the same structures, and the description thereof will not be repeated.

[A-1 Structure]

A reactor **1** according to Embodiment 1 will be described with reference to FIGS. 1 to 3. FIG. 1 is a perspective view of the reactor **1**. In FIG. 1, the horizontal direction is defined as an X-axis, the vertical direction is defined as a Y-axis, and the depth direction is defined as a Z-axis. FIG. 2 is a sectional view of the reactor **1** in an X-Z plane. FIG. 3 is a sectional view of the reactor **1** in a Y-Z plane which extends through the center of the ring of each of annular heat-dissipating cases **30** and **31**.

The reactor **1** includes a magnetic part **100** and a coil **90** wound around the magnetic part **100**. The magnetic part **100** includes a plurality of divided cores **10**, a core gap part **20** made of a non-magnetic material, the heat-dissipating cases **30** and **31**, and fixing parts **60** and **61**.

Each of the divided cores **10** has a shape obtained by dividing a general annular core in a circumferential direction. In other words, a combination of the plurality of divided cores **10** forms an annular core. The divided cores **10** are made of a soft magnetic material, and are dust cores, ferrite cores, amorphous cores, or nanocrystalline cores. When the divided cores **10** are dust cores, examples of the material contained in the divided cores **10** include pure iron, an Fe—Si alloy, an Fe—Si—Al alloy, an Ni—Fe alloy, and an Ni—Fe—Mo alloy. When the divided cores **10** are ferrite cores, examples of the material contained in the divided cores **10** include Mn—Zn ferrites or Ni—Zn ferrites. A powdered resin may be applied to the divided cores **10** for insulation.

Dust cores and ferrite cores are generally formed by molding a pulverulent material using a pressing machine and then performing a thermal process on the material. Here, the pressure to be applied to a pressed surface needs to be constant. As the cores are upsized, a pressing machine with higher press capacity needs to be used. Since the molded material shrinks in a thermal process, the dimensional precision is reduced as the cores are upsized. Amorphous cores and nanocrystalline cores are formed by laminating thin strip materials and then performing a thermal process on the materials. Since these cores also shrink in a thermal process similarly to the dust cores and the ferrite cores, the dimensional precision is reduced as the cores are upsized. Since each of the divided cores **10** has the shape obtained by dividing an annular core and is smaller than the annular core, the divided cores **10** can be easily manufactured and variations of dimensions in the manufacturing can be reduced.

The core gap part **20** is made of a non-magnetic material, for example, a resin or an insulating paper. Examples of the available resin contained in the core gap part **20** include polypropylene (PP), ABS, polyethylene terephthalate (PET), polycarbonate (PC), fluorine, phenol, melamine, polyurethane, epoxy, and silicon. Furthermore, examples of the available insulating paper contained in the core gap part **20** include kraft pulp, aramid, and a fiber.

The core gap part **20** is a unitary component consisting of a cylindrical part **23** and a plurality of thin plate parts **24** radially protruding from the outer circumferential surface of the cylindrical part **23**. The cylindrical part **23** of the core gap part **20** is disposed so that its outer circumferential surface is in contact with the inner circumferential surface of the annular core formed by combining the plurality of divided cores **10**. The plurality of divided cores **10** are disposed in the space outside the cylindrical part **23** that is

partitioned by the thin plate parts **24** of the core gap part **20**. Thus, the thickness of the thin plate part **24** is equal to the length of the core gap.

When the divided cores **10** are dust cores, the relative permeability of the dust cores is as small as approximately 26 to 150. Thus, the thickness of the thin plate parts **24** of the core gap part **20** is defined so that the total length of the core gaps ranges from approximately 0.1 to 2 mm. When the divided cores **10** are ferrite cores, the relative permeability of the ferrite cores is as high as 1500 to 4000. Thus, the thickness of the thin plate parts **24** of the core gap part **20** is defined so that the total length of the core gaps is increased as high as approximately 0.1 to 20 mm. As the number of the divided cores **10** and the number of the core gaps are many, the length of one of the core gaps is reduced. Thus, the eddy-current loss caused by the linkage of the magnetic flux leaked from the core gaps with the coil **90** can be reduced.

The core gap part **20** may be formed by superposing a plurality of core gap parts in the vertical direction. For facilitating the manufacture, the core gap part **20** may be fixed to the divided cores **10** with application of an adhesive to a part or all of the surfaces of the core gap part **20** that are in contact with the divided cores **10**. The core gap part **20** may include an annular part instead of the cylindrical part **23**.

Each of the heat-dissipating cases **30** and **31** is annular with one end surface opened. The heat-dissipating cases **30** and **31** house the divided cores **10** and the core gap part **20** from the opposite directions. The heat-dissipating case **30** includes protrusions **301** protruding vertically from the outer circumferential surface. Fixing holes **70** are formed in the protrusions **301**. Similarly, the heat-dissipating case **31** also includes protrusions **311** protruding vertically from the outer circumferential surface. The fixing holes **70** are formed in the protrusions **311**. As illustrated in FIG. 3, threadedly engaging fixing parts **61** in the fixing holes of the heat-dissipating cases **30** and **31** fasten the heat-dissipating cases **30** and **31**. The heat-dissipating cases **30** and **31** are made of a material whose thermal conductivity is as high as 100 W/(m·K) or more, for example, copper, aluminum, gold, silver, silicon, or nickel.

FIGS. 2 and 3 illustrate the two protrusions **311** and the two fixing holes **70**. The number of the fixing holes **70** in the heat-dissipating cases **30** and **31** is not limited to two but may be three or more. The fixing holes **70** are not limited to tapped holes but may be drilled holes.

FIG. 1 illustrates the heat-dissipating cases **30** and **31** with the same shape. The use of the same shape of the heat-dissipating cases **30** and **31** reduces costs. The heat-dissipating cases **30** and **31** may have different shapes as long as they come in contact with a part or all of the surfaces of the divided cores **10**. The thicker the heat-dissipating cases **30** and **31** are, the greater thermal diffusivity they have. Preferably, each of the heat-dissipating cases **30** and **31** is approximately 1 to 5 mm thick in consideration of the facilitation of the manufacture.

The fixing part **60** is disposed between the heat-dissipating cases **30** and **31** to avoid their direct contact. The fixing part **60** is made of, for example, a resin, an insulating paper, or a non-conductive adhesive. Examples of the resin contained in the fixing part **60** include polypropylene (PP), ABS, polyethylene terephthalate (PET), polycarbonate (PC), fluorine, phenol, melamine, polyurethane, epoxy, and silicon. Examples of the insulating paper contained in the fixing part **60** include kraft pulp, aramid, and a fiber.

FIG. 4 is an orthographic view of the fixing part **60**. The fixing part **60** includes an annulus **601** in contact with the

outer circumferential surfaces of the heat-dissipating cases **30** and **31**, and two protrusions **602** protruding from the annulus **601**. The protrusions **602** are portions in contact with the protrusions **301** and **311** of the heat-dissipating cases **30** and **31**, respectively, and each include a fixing hole **603** into which the fixing part **61** is inserted in alignment with the fixing hole **70**. In other words, inserting the fixing part **61** into the fixing hole **70** of the heat-dissipating case **30**, the fixing hole **603** of the fixing part **60**, and the fixing hole **70** of the heat-dissipating case **31** allows the heat-dissipating case **30** to be fixed to the heat-dissipating case **31** through the fixing part **60**.

The shape of the fixing part **60** illustrated in FIG. 4 is an example shape when the fixing part **60** is made of a resin or an insulating paper. When the fixing part **60** is made of a non-conductive adhesive, the fixing part **60** fixes the heat-dissipating case **30** and the heat-dissipating case **31**. Thus, the heat-dissipating cases **30** and **31** need not include the fixing holes **70**.

Since a current flows through the coil **90**, the coil **90** is made of copper or aluminum with a low electrical resistivity. To prevent short circuit in adjacent portions of the coil **90**, it is preferred that the coil **90** is insulation-coated or an insulating paper is wrapped around the coil **90**. Preferably, the insulation coating or the insulating paper is approximately 0.001 to 0.1 mm thick in view of preventing the short circuit in the adjacent portions of the coil **90**.

[A-2. Manufacturing Method]

Next, a method for manufacturing the reactor **1** will be described.

First, the divided cores **10** and the core gap part **20** are housed in the heat-dissipating case **31**. In this state, the lower portion of the divided cores **10** and the core gap part **20** is housed in the heat-dissipating case **31**, and the upper portion thereof protrudes from the heat-dissipating case **31**. Next, the fixing part **60** is disposed on the open end surface of the heat-dissipating case **31**. Further, the upper portion of the divided cores **10** and the core gap part **20** is housed in the heat-dissipating case **30**. Then, the fixing parts **61** are fastened to the fixing holes **70** of the heat-dissipating cases **30** and **31** to form the magnetic part **100**. Finally, the coil **90** is wound around the magnetic part **100** to form the reactor **1**.

[A-3. Advantages]

The heat generated from the divided cores **10** of the reactor **1** is dissipated to the atmosphere outside the reactor **1** (hereinafter simply referred to as “atmosphere”) through the following two routes.

A heat-dissipating route 1: the divided cores **10**→the heat-dissipating cases **30** and **31**→the coil **90**→the atmosphere

A heat-dissipating route 2: the divided cores **10**→the heat-dissipating cases **30** and **31**→the atmosphere

Since the heat-dissipating cases **30** and **31** are made of a material whose thermal conductivity is as high as 100 W/(m·K) or more as described above, the thermal resistance is low. Thus, the thermal resistance of the heat-dissipating route 2 is sufficiently low. Further, since the insulation coating of the coil **90** or the insulating paper wrapped around the coil **90** is approximately 0.001 to 0.1 mm thick, the thermal resistance is low. Further, since the coil **90** per se is made of copper or aluminum and the thermal conductivity is as high as 100 W/(m·K) or more, the thermal resistance is low. Thus, the thermal resistance of the heat-dissipating route 1 is sufficiently lower than those of the conventional structures. In other words, since the thermal resistances in

both of the heat-dissipating routes 1 and 2 are low, the high heat dissipation from the divided cores **10** can be achieved in the reactor **1**.

Further, disposing the outer circumferential surface of the cylindrical part **23** of the core gap part **20** in contact with the inner circumferential surface of the annular core formed by combining the plurality of divided cores **10** allows the divided cores **10** to be pressed toward the outer circumference of the heat-dissipating cases **30** and **31** and come in contact with the outer circumferential surface of the heat-dissipating cases **30** and **31**. The high heat dissipation from the divided cores **10** is achieved by dissipating the heat generated in the divided cores **10** not from the inner circumferential surface of the heat-dissipating cases **30** and **31** where the heat of the coil **90** is concentrated but from the outer circumferential surface of the heat-dissipating cases **30** and **31** where the heat of the coil **90** is not concentrated.

Further, a combination of the plurality of divided cores **10** forms a large annular core. Thus, the characteristic distributions caused by the manufacturing variations of the divided cores **10** can be minimized. This prevents, for example, local increase in the quantity of heat generated in the large annular core, and unifies the distribution of the heat of the annular core. Thus, the high heat dissipation is achieved.

Further, since the length of the core gap can be adjusted according to the thickness of the thin plate part **24** of the core gap part **20** with high precision, variations in the electrical performance caused by variations in the core gap can be suppressed.

Further, since the core gaps are distributed into a plurality of portions, the eddy-current loss of the coil **90** caused by the linkage of the magnetic flux leaked from the core gaps with the coil **90** is reduced.

The reactor **1** according to Embodiment 1 includes: the plurality of divided cores **10** having a shape obtained by dividing an annular core in a circumferential direction, the divided cores being made of a soft magnetic material; the core gap part **20** disposed between the divided cores **10** in the annular core formed by combining the plurality of divided cores **10**, the core gap part **20** being made of a non-magnetic material; the annular heat-dissipating cases **30** and **31** that house the divided cores **10** and the core gap part **20**; and the coil **90** wound around the heat-dissipating cases **30** and **31**. The heat-dissipating cases are made of a material whose thermal conductivity is as high as 100 W/(m·K) or more. Such a structure can dissipate the heat generated in the divided cores **10** from the heat-dissipating cases **30** and **31**, and increase the heat dissipation from the divided cores **10**.

Further, since the core gaps are distributed into a plurality of portions according to the number of divided cores **10**, the eddy-current loss of the coil **90** caused by the linkage of the magnetic flux leaked from the core gaps with the coil **90** is reduced. Further, the high heat dissipation from the divided cores **10** and reduction in the eddy-current loss of the coil **90** reduce increase in the temperature of the components included in the reactor **1**, which increases the capacity of the reactor **1**, downsizes the reactor **1**, and reduces the cost of the reactor **1**.

B. Embodiment 2

[B-1. Structure]

The structure of a reactor **2** according to Embodiment 2 will be described. FIG. 1 also illustrates the perspective view of the reactor **2**, which is identical to that of the reactor **1** according to Embodiment 1. FIG. 5 is a sectional view of the

reactor 2 in the Y-Z plane which extends through the center of the ring of each of the heat-dissipating cases 30 and 31.

The reactor 2 includes first heat-dissipating components 80 between the upper surface of the divided cores 10 and the heat-dissipating case 30 and further between the lower surface of the divided cores 10 and the heat-dissipating case 31. The structure of the reactor 2 other than the first heat-dissipating components 80 is identical to that of the reactor 1 according to Embodiment 1. As such, disposing the first heat-dissipating components 80 between the divided cores 10 and the heat-dissipating cases 30 and 31 reduces the thermal contact resistance between the heat-dissipating cases 30 and 31 and increases the heat dissipation from the divided cores 10 more than the case where the divided cores 10 are in direct contact with the heat-dissipating cases 30 and 31. Since the first heat-dissipating components 80 accommodate variations in dimensions of the divided cores 10 and the heat-dissipating cases 30 and 31, variations in the contact area between the divided cores 10 and the heat-dissipating cases 30 and 31 through the first heat-dissipating components 80 are suppressed among products.

The first heat-dissipating components 80 are made of a resin or rubber. Examples of the resin contained in the first heat-dissipating components 80 include polybutylene terephthalate (PBT), polyphenylene sulfide (PPS), and polyether ether ketone (PEEK). The first heat-dissipating components 80 may contain thermally conductive fillers in addition to these materials. Examples of the rubber contained in the first heat-dissipating components 80 include silicon and urethane. The first heat-dissipating components 80 may have rigidity or flexibility. To accommodate variations in dimensions of the divided cores 10 and the heat-dissipating cases 30 and 31, it is preferred that the first heat-dissipating components 80 are approximately 0.1 to 3 mm thick.

[B-2. Modifications]

The structure of a reactor 2A according to Modification 1 of Embodiment 2 will be described. FIG. 1 also illustrates the perspective view of the reactor 2A, which is identical to that of the reactor 1 according to Embodiment 1. FIG. 6 is a sectional view of the reactor 2A in the Y-Z plane which extends through the center of the ring of each of the heat-dissipating cases 30 and 31. The reactor 2A includes first heat-dissipating components 81 between the divided cores 10 and the heat-dissipating cases 30 and 31. The first heat-dissipating components 81 are formed between the outer circumferential surface of the divided cores 10 and the heat-dissipating cases 30 and 31, in addition to between the upper surface of the divided cores 10 and the heat-dissipating case 30 and between the lower surface of the divided cores 10 and the heat-dissipating case 31. The first heat-dissipating components 81 may contain a resin material such as epoxy with fluidity, in addition to the aforementioned materials of the first heat-dissipating components 80.

The surface of the divided cores 10 covered by the first heat-dissipating components 81 in the reactor 2A is larger than that of the divided cores 10 covered by the first heat-dissipating components 80 in the reactor 2. Thus, the thermal contact resistance between the divided cores 10 and the heat-dissipating cases 30 and 31 in the reactor 2A is lower than that in the reactor 2.

Since the first heat-dissipating components 81 fix the heat-dissipating cases 30 and 31, the heat-dissipating cases 30 and 31 do not require the fixing holes 70. Since there is no need to form the protrusions 301 and 311 for forming the fixing holes 70 on the outer circumferential surfaces of the heat-dissipating cases 30 and 31, the structures of the heat-dissipating cases 30 and 31 can be simplified. Further,

the manufacturing process of fastening the fixing parts 61 to the heat-dissipating cases 30 and 31 can be omitted.

The structure of a reactor 2B according to Modification 2 of Embodiment 2 will be described. FIG. 7 is a sectional view of the reactor 2B in the Y-Z plane which extends through the center of the ring of each of the heat-dissipating cases 30 and 31. The reactor 2B is obtained by forming the reactor 2A and then covering the periphery of the heat-dissipating cases 30 and 31 with a second heat-dissipating component 82. The second heat-dissipating component 82 contains a resin material such as epoxy with fluidity or a rubber material such as silicon or urethane. Consequently, the second heat-dissipating component 82 is filled between the adjacent portions of the coil 90 or between the coil 90 and the heat-dissipating cases 30 and 31. Thus, the heat dissipation from the divided cores 10 in the reactor 2B can be increased more than that in the reactor 2A.

[B-3. Advantages]

The reactor 2 according to Embodiment 2 and the reactor 2A according to Modification 1 of Embodiment 2 include the first heat-dissipating components 80 and the first heat-dissipating components 81, respectively, between the divided cores 10 and the heat-dissipating cases 30 and 31. Thus, the thermal contact resistance between the divided cores 10 and the heat-dissipating cases 30 and 31 is reduced, and the heat dissipation from the divided cores 10 is increased. Further, since the first heat-dissipating components 80 and 81 accommodate variations in dimensions of the divided cores 10 and the heat-dissipating cases 30 and 31, the variations in the contact area between the divided cores 10 and the heat-dissipating cases 30 and 31 through the first heat-dissipating components 80 and 81 are suppressed.

The reactor 2B according to Modification 2 of Embodiment 2 includes the second heat-dissipating component 82 between the adjacent portions of the coil 90 and between the coil 90 and the heat-dissipating cases 30 and 31. Thus, the high heat dissipation is achieved.

C. Embodiment 3

[C-1. Structure]

A reactor 3 according to Embodiment 3 will be described with reference to FIGS. 8 to 10. FIG. 8 is a perspective view of the reactor 3. In FIG. 8, the horizontal direction is defined as the X-axis, the vertical direction is defined as the Y-axis, and the depth direction is defined as the Z-axis. FIG. 9 is a sectional view of the reactor 3 in the X-Z plane. FIG. 10 is a sectional view of the reactor 3 in the Y-Z plane which extends through the center of the ring of an annular heat-dissipating case 33.

The reactor 3 includes the heat-dissipating case 33 instead of the heat-dissipating cases 30 and 31, and a third heat-dissipating component 83 on the upper surface of the divided cores 10. The structure of the reactor 3 other than the heat-dissipating case 33 and the third heat-dissipating component 83 is identical to that of the reactor 1 according to Embodiment 1.

The heat-dissipating case 33 is annular with one end surface opened, and houses the divided cores 10 and the core gap part 20. The heat-dissipating case 33 includes cutout portions 50 on the edge of the outer circumferential surface that is in contact with the open end surface. The heat-dissipating case 33 includes cutout portions 51 on the edge of the inner circumferential surface that is in contact with the open end surface. The coil 90 is wound around the heat-dissipating case 33 along the cutout portions 50 and 51. Since the cutout portions 50 and 51 guide the coil 90, not

only manual winding of the coil 90 is facilitated but also a mistake in the number of windings is prevented. Thus, the manufacturing cost of the reactor 3 is reduced.

As illustrated in FIG. 9, the cutout portions 50 on the outer circumferential surface of the heat-dissipating case 33 are disposed distant from the thin plate parts 24 of the core gap part 20 so that the coil 90 wound along the cutout portions 50 does not overlap the coil gaps. This reduces the eddy-current loss caused by the linkage of the magnetic flux leaked from the core gaps with the coil 90.

The heat-dissipating case 33 is made of a material whose thermal conductivity is as high as 100 W/(m·K) or more, for example, copper, aluminum, gold, silver, or silicon.

The thicker the heat-dissipating case 33 is, the greater thermal diffusivity it has. Preferably, the heat-dissipating case 33 is approximately 1 to 5 mm thick in consideration of the facilitation of the manufacture.

The third heat-dissipating component 83 is an annular plate or block. The third heat-dissipating component 83 is made of a material whose thermal conductivity is as high as 100 W/(m·K) or more, for example, copper, aluminum, gold, silver, silicon, or nickel. The thicker the third heat-dissipating component 83 is, the greater thermal diffusivity it has. Preferably, the third heat-dissipating component 83 is approximately 1 to 5 mm thick in consideration of the facilitation of the manufacture. The third heat-dissipating component 83 may be in contact with the heat-dissipating case 33. The third heat-dissipating component 83 is structured so that the third heat-dissipating component 83 avoids contact with both of the cutout portions 50 on the outer circumferential surface of the heat-dissipating case 33 and the cutout portions 51 on the inner circumferential surface thereof by reducing a width w2 of the third heat-dissipating component 83 more than a width w1 of the heat-dissipating case 33. This prevents the heat-dissipating case 33 and the third heat-dissipating component 83 from functioning as a one-turn coil relative to the cross-section of the divided cores 10.

[C-2. Advantages]

In the reactor 3 according to Embodiment 3, one end surface of the heat-dissipating case 33 is an opened end surface. The heat-dissipating case 33 includes the cutout portions 50 and the cutout portions 51 on the edges of the outer circumferential surface and the inner circumferential surface, respectively, which are in contact with the opened end surface. The coil 90 is wound along the cutout portions 50 and 51. Thus, using the cutout portions 50 and 51 as guides, manual winding of the coil 90 can be facilitated. Further, a mistake in the number of windings is prevented. Thus, the manufacturing cost of the reactor 3 is reduced.

D. Embodiment 4

[D-1. Structure]

A reactor 4 according to Embodiment 4 will be described with reference to FIGS. 11 to 12. FIG. 11 is a sectional view of the reactor 4 in the X-Z plane. FIG. 12 is a sectional view of the reactor 4 in the Y-Z plane which extends through the center of the ring of an annular heat-dissipating case 34.

The reactor 4 includes the heat-dissipating case 34 instead of the heat-dissipating case 33 of the reactor 3. The structure of the reactor 4 other than the heat-dissipating case 34 is identical to that of the reactor 3 according to Embodiment 3.

One end surface of the heat-dissipating case 34 is an opened end surface. The edge of the outer circumferential surface of the heat-dissipating case 34 that is in contact with the open end surface has protrusions 341 protruding outside

the heat-dissipating case 34 from the edge. Each of the protrusions 341 is formed by, for example, bending, into an L-shape, a portion sandwiched by two of the cutout portions 50 on the outer circumferential surface of the heat-dissipating case 33 according to Embodiment 3. The structure of the heat-dissipating case 34 other than the protrusions 341 is identical to that of the heat-dissipating case 33 according to Embodiment 3. The protrusions 341 include fixing holes 72. The heat-dissipating case 34 is fixed to a cooler 200 using 10 fixing parts 62 inserted into the fixing holes 72.

The cooler 200 is fixed to the heat-dissipating case 34 while covering the open end surface of the heat-dissipating case 34. Thus, the heat generated in the divided cores 10 is dissipated to the cooler 200 through the heat-dissipating case 34. Further, the heat generated in the coil 90 is dissipated to the cooler 200 through the third heat-dissipating component 83. Since the thermal resistance from the cooler 200 to the atmosphere is very low, increasing the surface area of the cooler 200 more than the surface area of the heat-dissipating case 34 increases the heat dissipation from the divided cores 10 and the coil 90.

The cooler 200 is made of a material whose thermal conductivity is as high as 100 W/(m·K) or more, for example, copper, aluminum, gold, silver, silicon, or nickel.

The cooling system of the cooler 200 may be any systems including natural air cooling, forced-air cooling, and liquid cooling.

The breakdown voltage is required between the divided cores 10 or the coil 90 and the cooler 200. When the insulation coating of the divided cores 10 or the coil 90 cannot maintain a sufficient breakdown voltage, a resin or an insulating paper may be formed between the divided cores 10 or the coil 90 and the cooler 200 as an insulating material. Here, examples of the resin include polypropylene (PP), 30 ABS, polyethylene terephthalate (PET), polycarbonate (PC), fluorine, phenol, melamine, polyurethane, epoxy, silicon, and polybutylene terephthalate (PBT), polyphenylene sulfide (PPS), and polyether ether ketone (PEEK) which contain thermally conductive fillers. Further, examples of 35 the available insulating paper include kraft pulp, aramid, and a fiber.

When the insulating material is formed, the thermal resistance between the divided cores 10 and the cooler 200 increases. However, since the thermal resistance between 45 the cooler 200 and the atmosphere is low, there is no problem in the heat dissipation from the divided cores 10 and the coil 90. Moreover, the sufficient breakdown voltage can be maintained between the divided cores 10 or the coil 90 and the cooler 200.

[D-2. Advantages]

In the reactor 4 according to Embodiment 4, one end surface of the heat-dissipating case 34 is an opened end surface, the heat-dissipating case 34 includes the protrusions 341 protruding from the edge of the outer circumferential surface that is in contact with the open end surface, and the protrusions 341 are fixed to the cooler 200 disposed on the open end surface of the heat-dissipating case 34. This can dissipate the heat generated in the divided cores 10 or the coil 90 to the cooler 200, which improves the heat dissipation 55 from the divided cores 10 and the coil 90.

E. Embodiment 5

Embodiments 1 to 4 describe the core gap part 20 as a 60 unitary component consisting of the cylindrical part 23 and the plurality of thin plate parts 24. In contrast in Embodiment 5, the core gap part 20 consists of a combination of a

11

plurality of components each separately formed. Hereinafter, a reactor **5** according to Embodiment 5 will be described as an example structure in which the core gap part **20** according to Embodiment 1 consists of the combination of the plurality of components each separately formed. Embodiment 5 is also applicable to Embodiments 2 to 4. [E-1. Structure]

The reactor **5** according to Embodiment 5 will be described with reference to FIGS. 13 to 16. FIG. 1 also illustrates the perspective view of the reactor **5**, which is identical to that of the reactor **1** according to Embodiment 1. FIG. 13 is a sectional view of the reactor **5** in the X-Z plane. FIG. 14 is a sectional view of the reactor **5** in the Y-Z plane which extends through the center of the ring of the annular heat-dissipating case **31**. FIG. 15 is an orthographic view of a first core gap part **21**, and FIG. 16 is an orthographic view of second core gap parts **22**.

The core gap part **20** of the reactor **5** consists of a combination of the cylindrical first core gap part **21** and the laminar second core gap parts **22**. The structure of the reactor **5** other than the core gap part **20** is identical to that of the reactor **1** according to Embodiment 1.

As illustrated in FIG. 15, the cylindrical first core gap part **21** includes eight cutout portions **52** corresponding to the number of the second core gap parts **22**. As illustrated in FIG. 16, the laminar second core gap parts **22** include cutout portions **53** corresponding to the cutout portions **52** of the first core gap part **21**. The core gap part **20** is formed with a combination of the first core gap part **21** and the second core gap parts **22** by inserting the second core gap parts **22** into the cutout portions **52** of the first core gap part **21** so that the cutout portions **53** of the second core gap parts **22** fit the cutout portions **52** of the first core gap part **21**.

The first core gap part **21** and the second core gap parts **22** are made of a non-magnetic material such as a resin or an insulating paper. Examples of the resin contained in the first core gap part **21** and the second core gap parts **22** include polypropylene (PP), ABS, polyethylene terephthalate (PET), polycarbonate (PC), fluorine, phenol, melamine, polyurethane, epoxy, and silicon. Examples of the insulating paper contained in the first core gap part **21** and the second core gap parts **22** include kraft pulp, aramid, and a fiber.

FIG. 15 illustrates the eight cutout portions **52** the number of which corresponds to the number of the second core gap parts **22**. When the number of the second core gap parts **22** is changed, the number of the cutout portions **52** is accordingly changed. Further, the first core gap part **21** is cylindrical, and the second core gap parts **22** are laminar according to Embodiment 5. Since the shapes of the first core gap part **21** and the second core gap parts **22** are simple in this example, the manufacturing cost can be reduced. However, the shapes of the first core gap part **21** and the second core gap parts **22** are not limited to these.

[E-2. Advantages] In the reactor according to Embodiment 5, the core gap part **20** includes: the first core gap part **21** including the plurality of cutout portions **52**; and a plurality of the second core gap parts **22** to be inserted into the plurality of cutout portions **52** of the first core gap part **21**. As such, forming the core gap part **20** with a combination of the plurality of components can facilitate the manufacturing of the core gap part **20**.

F. Embodiment 6

Embodiment 5 describes that the core gap part **20** consists of a combination of the cylindrical first core gap part **21** and the laminar second core gap parts **22**. Embodiment 6 will

12

describe various modifications of the first core gap part **21**. Embodiment 6 is also applicable to Embodiments 2 to 4. [F-1. Structure]

FIG. 17 is an orthographic view of a first core gap part **25**. The first core gap part **25** is identical to the first core gap part **21** except for having bumps **26** on the outer circumferential surface of the cylindrical part.

The advantages of the first core gap part **25** are as follows. In processes of manufacturing a reactor, the first core gap part **25** and then the divided cores **10** are inserted into the heat-dissipating case **31**. Here, the divided cores **10** abut the bumps **26** of the first core gap part **25**, and are pressed toward the outer circumference of the heat-dissipating case **31**. Thus, the divided cores **10** are reliably in contact with the outer circumferential surface of the heat-dissipating case **31**, which significantly increases the heat dissipation from the divided cores **10** as described in Embodiment 1.

FIG. 18 is an orthographic view of a first core gap part **27**. The first core gap part **27** is identical to the first core gap part **21** except for being tapered toward the direction of the cylindrical axis.

The advantages of the first core gap part **27** are as follows. In processes of manufacturing a reactor, the first core gap part **27** and then the divided cores **10** are inserted into the heat-dissipating case **31**. Here, the divided cores **10** abut the first core gap part **27**. Since the first core gap part **27** is tapered toward the direction of the cylindrical axis, the divided cores **10** are pressed toward the outer circumference of the heat-dissipating case **31**, and are reliably in contact with the outer circumferential surface of the heat-dissipating case **31**. Thus, the heat dissipation from the divided cores **10** is significantly increased as described in Embodiment 1.

FIG. 19 is an orthographic view of a first core gap part **28**. The first core gap part **28** is a cylindrically wound thin plate, and includes eight cutout portions **54** corresponding to the number of the second core gap parts **22** in the thickness direction. The second core gap parts **22** are inserted into the cutout portions **54** which have functions similar to those of the cutout portions **52** in the first core gap part **21**.

The advantages of the first core gap part **28** are as follows. In processes of manufacturing a reactor, the first core gap part **28** is cylindrically wound, and inserted into the heat-dissipating case **31**. Then, the divided cores **10** are inserted into the heat-dissipating case **31**. Here, the first core gap part **28** spreads toward the outer circumference of the heat-dissipating case **31** with the stress of restoring the first core gap part **28** to its laminar shape. This stress presses the divided cores **10** toward the outer circumference of the heat-dissipating case **31**. Thereby, the divided cores **10** are reliably in contact with the outer circumferential surface of the heat-dissipating case **31**. Thus, the heat dissipation from the divided cores **10** is significantly increased as described in Embodiment 1.

[F-2. Advantages]

The first core gap part **25** is cylindrical, and includes bumps **26** on the outer circumferential surface. When the first core gap part **25** is used in a reactor, the divided cores **10** inserted into the heat-dissipating case **31** abut the bumps **26** of the first core gap part **25**, and are pressed toward the outer circumference of the heat-dissipating case **31**. Thus, the divided cores **10** are reliably in contact with the outer circumferential surface of the heat-dissipating case **31**, which increases the heat dissipation.

The first core gap part **27** is cylindrical, and the outer circumferential surface of the first core gap part **27** is tapered toward the direction of the cylindrical axis. When the first core gap part **27** is used in a reactor, the divided cores **10**

13

inserted into the heat-dissipating case 31 are pressed toward the outer circumference of the heat-dissipating case 31 along the outer circumferential surface of the first core gap part 27, and are reliably in contact with the outer circumferential surface of the heat-dissipating case 31. This increases the heat dissipation from the divided cores 10.

The first core gap part 28 is a cylindrically wound thin plate. When the first core gap part 28 is used in a reactor, it is cylindrically wound, and inserted into the heat-dissipating case 31. Thus, the divided cores 10 inserted into the heat-dissipating case 31 are pressed toward the outer circumference of the heat-dissipating case 31 with the stress of restoring the first core gap part 28 to its laminar shape, and are reliably in contact with the outer circumferential surface of the heat-dissipating case 31. This increases the heat dissipation from the divided cores 10.

Embodiments can be freely combined, and appropriately modified or omitted within the scope of the present invention. Although this invention has been described in detail, the description is in all aspects illustrative and does not restrict the invention. It is therefore understood that numerous modifications and variations that have yet been exemplified can be devised without departing from the scope of the invention.

EXPLANATION OF REFERENCE SIGNS

1, 2, 2A, 2B, 3, 4, 5 reactor, 10 divided core, 20 core gap part, 21, 25, 27, 28 first core gap part, 22 second core gap part, 23 cylindrical part, 24 thin plate part, 26 bump, 30, 31, 33, 34 heat-dissipating case, 50, 51, 52, 53, 54 cutout portion, 60, 61, 62 fixing part, 70, 72, 603 fixing hole, 80, 81 first heat-dissipating component, 82 second heat-dissipating component, 83 third heat-dis-

14

sipating component, 90 coil, 100 magnetic part, 200 cooler, 301, 311, 341, 602 protrusion, 601 annulus.

The invention claimed is:

1. A reactor, comprising:
a plurality of divided cores having a shape obtained by dividing an annular core in a circumferential direction, the divided cores being made of a soft magnetic material;
a core gap part disposed between the divided cores in the annular core formed by combining the plurality of divided cores, the core gap part being made of a non-magnetic material;
an annular heat-dissipating case that houses the divided cores and the core gap part; and
a coil wound around the heat-dissipating case,
wherein,
one end surface of the heat-dissipating case is an open end surface,
the heat-dissipating case includes cutout portions on edges of an outer circumferential surface and an inner circumferential surface that are in contact with the open end surface,
the coil is wound along the cutout portions, and
the cutout portions in the heat-dissipating case are disposed distant from the core gap part so that the coil wound along the cutout portions is disposed only in a region overlapping the divided cores.

2. The reactor according to claim 1,
wherein the heat-dissipating case includes protrusions protruding from an edge of an outer circumferential surface that is in contact with the open end surface, and the protrusions are fixed to a cooler disposed on the open end surface of the heat-dissipating case.

* * * * *
